BODY GARMENT

Maude C. Fridolph, Los Angeles, Calif.

Application May 26, 1945, Serial No. 595,895

9 Claims. (Cl. 2—43)

1

This invention relates to a body garment and has particularly to do with a hip encircling garment commonly called a girdle.

In order to give a smooth line across the abdomen and to control firmly the thigh and buttock muscles, a corset, girdle or one piece garment must be relatively snug throughout. Firm support and snug tension can be and is maintained in such garments from waist line down to hip joint or approximately the point across the widest part of the hips without discomfort to the wearer. But the necessary tension which must be maintained below these points automatically restricts the stride of the wearer when walking and also causes the garment to cut into the thighs when the wearer is seated. This is probably due to the fact that the circumferential distance of the lower edge is less than the circumferential distance at the center part and cannot, therefore, expand sufficiently to be comfortable when the wearer walks or sits. On the other hand if the lower circumferential distance is increased the garment would then not give the necessary support and would also slide upwardly on the body.

Certain efforts have been made to relieve this tension by providing two-way stretch garments, elastic gores, providing all rubber garments, etc. But, this has not been a satisfactory solution to the problem.

It is an object of the present invention to provide a construction and design which, while furnishing the necessary snug fit and firm support, nevertheless relieves the tension along the lower edge of the garment particularly in walking and sitting. In effect the circumferential distance at the edges of the girdle is increased without relaxing the support or molding qualities of the garment. Other objects of the invention include a basic panel design which will release tension without losing the necessary support at any point where snug fit and/or freedom of action is desired.

Other objects and features of the invention having to do with details of construction and the relationship of the parts of the garment, will be evident in the following description and claims:

In the drawings:

Fig. 1 is a view of a female figure with the garment in position.

Fig. 2 is a view of one version of the garment laid out in open position.

Fig. 3 is a front view of one version of the garment as it is worn.

2

Fig. 4 is a view similar to Fig. 3, portions of the front panel opened to show the construction.

Fig. 5 is a rear view of the garment illustrating the manner in which the rear panel could be modified without altering the function.

Fig. 6 is a side view of the garment as it appears on the body.

Basically the garment as illustrated in the drawings consists of double front panel, a double back panel and connecting side panels which have circumferential elasticity at least in the lower portion. In Fig. 2 the front panel is shown at 10, the rear panel at 11 and the side panels at 12 and 13. Side panels may be single pieces of fabric but preferably have a circumferential elastic portion 14 which may be two-way or single stretch material. If desired the entire side panel may be of one-way or two-way stretch material.

The front panel consists of two identical pieces 15 and 16 which are reversed and placed in overlying relation and sewn together at the edges 17, 18 and 19. At the edge 18 the two front panels are connected to the side panel 12. The weave lines of the panels 15 and 16 are disposed at an angle to horizontal and to each other so that they cross as shown by the arrows on Figs. 2 and 3. The lower edges 20 and 21 are substantially parallel with the weave lines and each angles upwardly to the points x and y. These edges 20 and 21 overlie each other freely without connection.

The back panel 11 is composed of this double construction with panels 25 and 26 connected to the side panels at 27 and 28 and connected together at 29. Edges 30 and 31, parallel to the weave lines of the respective panels, are disposed in angular relation to the edge of the garment and to each other. Suitable hooks 35 on edge 19 cooperate with eyes 36 on the strip 37 to provide an opening seam for the garment; the garment may also be hooked part way or made as a step-in without any side opening.

The points x and y shown on the drawings correspond approximately to the trochanter region of the femur bone. Ignoring the back panel construction for the moment, the garment may be considered a double ended piece with panels 15 and 16 comprising the ends. The rear portion encircles the body with the lines of the garment substantially horizontal, one across the sacroiliac region of the back at the top and one below the buttocks at the bottom. The garment then sweeps around the body in a sling-like fashion with the lower edges sweeping upward-

ly at an angle to each other and crossing at the point *w* (Fig. 3).

The foundation of stress of the entire garment at the trochanter points of the femur bones, points *x* and *y*, and the cross connection from the trochanter on one side to the base on the other side and vice versa provides a confining garment which operates in a manner to free the leg muscles when the wearer is walking or exercising and releases the tension when the wearer sits. In addition the upward lift of the garment to the points *x* and *y* cooperate with the elastic portions 14, provides a firm support for each buttock and a cradle-like support for the abdomen with a comfortable lift to the pelvic organs. The overlapping of edges 20 and 21 lying between points GX and FY in crossing each other at the point *w* prevent the garment from rolling upward because of the division of force and the overlapping relation.

The construction of the back panel 11 is also calculated to relieve certain strains and tension that develop at the sacro-ilium region and to give in some measure the exact effect on the back that it performs in the front.

In Fig. 5 a modification of this back panel 11 is composed of a single fabric piece 45 having an angularly disposed edge 46 connected at R to the seam 47. The other side, panel 13, is connected to seam 48 by a strip 50 extending from the point 51 to the point S on seam 48 along the edge 52. The weave lines of piece 50 are parallel to the edge 52 as are the weave lines of piece 45 of weave lines parallel to 46.

In Figs. 3 and 4 garters are shown attached to points F and G. As shown in the drawings the portions XF and YG or edges 18 and 19 respectively are curved along the natural hip curve to the bottom of the sling-like construction. In such curve the portions XF and YG of edges 18 and 19 respectively, lie substantially at right angles to edges 20 and 21 lying between points FY and GX. The tension is thus transferred evenly over the garment at these points. The fastening of garters at points F and G simply aids the sling action without destroying the limb freedom at the front of the garment.

What I claim is:

1. A girdle comprising a multiple-panel body encircling construction, having side panels formed at least in part of elastic material, and front and back panels each comprising two non-elastic fabric pieces narrowed progressively from one side to the other and arranged each with one free edge and weave lines disposed in unconnected relation at an angle to the other, the angled free edges of the front fabric pieces being at the lower portion of the garment at the pubic region of the body and the angled free edges of the back panel being at the top of the garment at the sacro-ilium region of the body, the side edges being connected together and to the side panels.

2. A body confining garment to be located at the hip region which comprises encircling portions having circumferential elasticity below the widest portion of the hips and overlapping unconnected panel portions at the front of the garment disposed in angular relation at one edge at least, the crossed edges of the panel portions being anchored at points inside the normal boundary of the garment, the side contours of the crossed, overlapping panel portions approximating the natural hip curve from the widest portion to the bottom edge of the panel portions.

3. A body confining garment to be located at

the hip region which comprises encircling portions having circumferential elasticity below the widest portion of the hips and overlapping unconnected panel portions at the front of the garment disposed in angular relation at one edge at least, the crossed edges of the panel portions being anchored at points inside the normal boundary of the garment, the side contours of the crossed, overlapping panel portions approximating the natural hip curve from the widest portion to the bottom edge of the panel portions, and garters fastened at the lowest point of such side contours of the front panel portions.

4. A body confining garment to be located at the hip region which comprises body encircling portions, the lower edges of which are substantially horizontally disposed below the buttocks at the back and sides, and overlapping at the front, the lower edge of each overlapping front portion crossing the pelvic region at a rising angle and extending substantially perpendicular from the natural hip curve at the lower portion of the garment to the trochanter region on the opposite side.
5. A girdle comprising a multiple-panel body encircling construction having a back panel encircling the buttocks, side panels stretchable in at least that portion below the hips, said side and back panels having lower edges substantially horizontal when on the wearer, a front panel with side contours approximating the natural hip curve extending outwardly to the trochanter region at its widest section and composed of two overlapping fabric pieces having lower edges rising from the lower edges of the side panels substantially perpendicular to the lower ends of the side contours of the front panel and extending substantially to the region of the trochanter of the femur bone on the opposite sides.
6. A girdle comprising a multiple panel body encircling construction, a front panel being composed of two thicknesses of nonelastic fabric having side contours approximating the hip curve and extending to the trochanter region at its widest section, side panels stretchable in at least that portion below the widest part of the body, one of said side panels having a front side edge substantially straight when unassembled and conforming to the natural hip curve when the garment is assembled and positioned on the body.
7. A girdle of the multiple panel body encircling type comprising a front panel comprising two thicknesses of nonelastic fabric having side contours the lower ends of which approximate the hip curve, side panels at least a portion of which are elastic, extending from a back panel around the back and sides of the buttocks to said curved side contours of said front panel, the lower edges of said side panels being continued upward by the lower edges of the fabrics of said front panel substantially perpendicular to the lower ends of said side contours to said front panel, said edges crossing at a point adjacent the pubic region and anchored on the opposite sides of said front panel adjacent the trochanter of the femur bone, whereby a hammock-like support is provided for each buttock, the fulcrum of said supports being at the trochanter region opposite the buttock supported.
8. A body confining garment to be located at the hip region which comprises encircling portions having upper edges substantially in a horizontal plane above the hips when on the wearer and overlapping on the abdominal region, the lower edge of the garment being substantially

horizontally disposed below the buttocks at the back and sides overlapping freely at the front, the lower edge of each freely overlapping front portion crossing the pelvic region in a rising angle to an anchoring point on the other overlapping portion approximately at the trochanters of femur bone.

9. A body confining garment to be located at the hip region, comprising a back portion having a lower edge disposed below the buttocks when on the wearer, side portions having lower edges substantially extensive with the lower edge of the back portion and a front portion comprising overlapping pieces of material adapted when on the wearer to pull up against the side portions at an upwardly inclined angle across the lower part of the abdomen, the lower edges of the overlapping pieces of material extending respectively from the lower edges of the side portions upwardly and being connected to the opposite side portion at points adjacent the trochanters of the femur bone whereby to form two independent hammock ends anchored at approximately the trochanters of the femur bone and extending across each

other and downwardly and rearwardly to support the buttocks.
